MECHANISM FOR VERIFYING PATTERN CARDS
Frederick C. Wiesinger, Feasterville, Pa., assignor to Wildman Jacquard Co., Norristown, Pa., a corporation of Pennsylvania

Filed Apr. 15, 1963, Ser. No. 273,076

5 Claims. (Cl. 73—156)

This invention relates to the art of knitting and, more particularly, to the programming cards utilized in circular jacquard knitting machines.

It is a general object of the invention to provide a verifying means for checking pattern cards.

It is a further object of the invention to provide a mechanical means of verifying a pattern card by checking it against a master pattern card.

It is a further object of the invention to provide a pattern card verifying mechanism that can be adapted to function in conjunction with a pattern card duplicating machine.

It is a still further object of the invention to provide a pattern card verifying mechanism which will automatically cease to function should a variation from the master pattern card be detected.

Other objects and advantages of the invention will become apparent from the following more detailed disclosure.

Pattern cards of the type utilized in circular jacquard knitting machines are produced in a pattern card duplicating machine well known to those conversant in the art such as the duplicating machines manufactured and sold by the Wildman Jacquard Co., of Norristown, Pennsylvania.

These machines utilize a master pattern card which, by means of a plurality of sensing levers being in contact therewith, influences the levers in such a manner so as to transmit its dictates to the punching apparatus to form identical perforations on a new card being formed as those on said master card.

The means of verifying or checking these pattern cards prior to the instant invention has been by visual comparison with a master card. This procedure has been slow and tedious and in view of the human element involved has not always been completely effective.

According to the instant invention, a mechanical means can now be employed to verify a pattern card to determine if the pattern perforations formed thereon are the same as those on the master pattern card.

These pattern cards are formed on a duplicating machine from sheet-like material and since a plurality of like cards are used on a single knitting machine, the required number are formed on a single strip of this material with the necessary spacing between each group of pattern perforations to permit said strip to be divided into individual pattern cards.

The verifying mechanism according to the invention is adapted to function in conjunction with the duplicating machine. It includes a first and second drum member, the first of which supports and guides a second master pattern card and the second drum member is adapted to support and guide the newly formed perforated strip comprising the number of duplicated pattern cards required.

A plurality of dual sensing levers are disposed above the drum members and said levers are caused to reciprocate vertically. The drum members are caused to move in increments equivalent to the spacing of the parallel rows of pattern perforations on the cards, moving the cards therewith and in timed relation with the reciprocation of the sensing levers. The master pattern card and the strip of perforated cards being compared there-

2

with are caused to move synchronously over the drum members. If a variation is detected in the cards being compared by one or more of the sensing levers, the complete operation will be discontinued by means of an electrically controlled stop motion adapted for that purpose. Verifying pattern cards in this manner and stopping the machine in the event of a variation in the cards prevent an excessive number of incorrect pattern cards from being formed as well as eliminating the time and waste of material that could be had and that have been experienced prior to the instant invention.

The invention will be described in greater detail hereinafter by reference to the accompanying figures of drawing, wherein:

FIG. 1 is a perspective view showing a portion of a duplicating machine and the verifying mechanism according to the invention applied thereto;

FIG. 1-A is a perspective view of the comb-like member utilized to position and guide the upper portion of the sensing levers;

FIG. 2 is a view in front elevation of the verifying mechanism minus its cover plates, and showing the various components thereof for turning the drum members (not shown), means for reciprocating and manually raising the sensing levers, and in order to show clearly the lower portion of said sensing levers, the idler tension roller has been illustrated elevated above that position to which it can be raised.

FIG. 3 is a view in side elevation as seen looking from the right-hand side of the verifier showing the sensing levers, their means of vertical reciprocation, the pattern cards and the direction they are caused to move over the drum members which are incrementally rotated by rosette wheels attached thereto.

FIG. 4 is a sectional view of a portion of the verifier as seen looking in the direction of the indicating arrows 4—4 in FIG. 3, showing the means for incrementally turning the drum members;

FIG. 5 is a view in side elevation as seen looking from the left-hand side of the verifier showing the drive means utilized to obtain the desired motions to reciprocate the sensing levers and rotate the drum members;

FIG. 6 is a view similar to that of FIG. 5 but partially in section having the side portion thereof cut away to show the gearing required to transmit the required motion to the sensing levers and drum members;

FIG. 7 is a view in side elevation and partially in section showing the relationship of the sensing levers with the drum members and pattern cards being compared; also the sensing lever is shown at its highest point during vertical reciprocation;

FIG. 8 is a view similar to that of FIG. 7 but showing the sensing lever at its lowermost position and with the sensing portions thereof extending through the perforations in the pattern cards and into the longitudinal grooves provided on the outer periphery of the drum members;

FIG. 9 is a view similar to both FIGS. 7 and 8 but showing the tilted position the sensing lever is caused to assume should it detect a variation in the pattern cards being compared;

FIG. 10 is a wiring diagram of the electrical circuit utilized during the actual running of the duplicating machine in combination with the verifying mechanism according to the invention; and

FIG. 11 is a wiring diagram of the electrical circuit which acts to stop the entire operation of punching and verifying should a variation in the pattern cards being compared be detected.

Now referring to FIG. 1, a pattern card duplicating machine to which the invention may be applied comprises a punching head 20, a plurality of pattern indicating levers 21 which are caused to transmit the dictates of a first

master pattern card 22 to said punching head. The master card is supported and guided by a pattern drum 23 which is caused to rotate in a clockwise direction and in increments equivalent to the spacing of horizontal parallel rows of pattern perforations on the master pattern card.

The master pattern card 22 being of the endless type is provided with a weighted roll 24 to maintain said card in general vertical alignment with pattern drum 23. This drum is provided with longitudinally extending grooves (not shown) disposed about the entire outer periphery of the drum and spaced to align with the perforations in the master pattern card. The pattern indicating levers 21 are continually urged to the forward or left-hand side position depicted in FIG. 1, as well as downwardly, by individual coil springs 25 attached to the levers as at 26 and to the machine itself as at 27. Each indicating lever 21 is provided on its underside and adjacent the forward end thereof with spring biased pin members 28 (one only shown in FIG. 1). These pin members are caused to bear against the master pattern card and as this card is advanced by drum 23, the pin members 28 which become aligned with the pattern perforations will pass through them and thence into the longitudinal extending groove in the drum. As drum 23 continues to move, it will push each indicating lever 21 whose pin 28 is in register or alignment with a pattern perforation in that particular row inwardly toward the punching head 20. In this manner, the dictates of the master pattern card are transmitted to the punching head causing identical perforations to be formed on pattern card material 29 being fed into and through said punching head, all in a known manner.

This pattern card material is drawn from a supply spool 30 suitably positioned beneath the machine itself.

The machine receives its means of motion through a driven shaft 31 which is caused to be rotated by any suitable form of power. Shaft 31 extends transversely of and beyond the opposite side of the machine and provides a source of power at this point that is utilized to initiate movement of the various components of the verifying mechanism according to the invention to be detailed hereinafter.

Shaft 31 is also provided with a clutch member 32 which can be engaged or disengaged by a lever member 33 which is pivotally attached to the machine intermediate its ends as at 34. The inner end of lever 33 is engageable with the clutch as at 35 and its opposite end is pivotally attached as at 36 to the actuating arm 37 of an electrically controlled solenoid 38. This solenoid member is interconnected with the means for manually starting and stopping the machine as well as the automatic stop motion forming a part of the invention to stop the entire operation should a variation be detected in the pattern cards being compared.

The pattern card duplicating mechanism is mounted and supported on a table-like structure 39 and the verifying mechanism according to the invention, which is generally indicated by numeral 40, is attached to said structure rearwardly of the card duplicating mechanism and in a position where it is adapted to receive the strip of pattern card material 29, having perforations thereon, as it comes from the punching head 20.

The mechanism according to the invention includes a first casing 41 and is supported by a rearwardly directed extension 42 which as seen looking from the front of the machine is attached to the left rear supporting member of structure 39. This casing is attached to extension 42 by means of cap screws 43 (FIG. 6).

A second casing 44 situated in general alignment with the pattern card strip being formed assembles against the inner side of and intermediate the ends of the first casing 41 by means of cap screws 45 and 46 (FIGS. 2, 5, and 6).

Casing 41 houses the proper gearing necessary to effect movement of the various components which make up

the invention and includes a sprocket 47 on the outside of and in close proximity with the outer wall of said casing 41 (FIG. 5) and is interconnected by a chain 48 to a similar sprocket (not shown) assembled on that end of driven shaft 31 opposite the clutch member 32.

An idler sprocket 49 disposed below and slightly rearward of sprocket 47 is also in mesh with chain 48. This idler sprocket is freely rotatable on a stud member 50 and assembles in a vertical slot 51 provided in the outer side wall of casing 41. Slot 51 permits vertical adjustment of stud 50 and the idler sprocket 49 and serves as a means for adjusting the tension under which the chain 48 is caused to travel.

Sprocket 47 assembles on the outer end of a driving shaft 52 which is journaled in the outer and inner walls of casing 41 and extends beyond the inner wall for a purpose to be described hereinafter.

Within the confines of casing 41 there is provided a first gear member 53 fixedly positioned on shaft 52 and in close proximity with the inner wall of casing 41. Gear member 53 is in meshing relation with an idler gear 54 that is freely rotatable on a shaft 55 which is in horizontal alignment with shaft 52 and which is also journaled in both the outer and inner walls of casing 41.

A third shaft 56 is also in horizontal alignment with shafts 52 and 55 and is journaled in a like manner in casing 41. The inner end of shaft 56 extends through and beyond the inner wall of casing 41 and serves a purpose like that of shaft 52 which will be described hereinafter in greater detail. Shaft 56 is provided with a second gear member 57 (FIG. 6) fixedly attached thereto and in meshing relation with the idler gear 54. To prevent longitudinal movement of shafts 52, 55, and 56 they are provided with collars 58 adjacent their respective gear members and adjacent their journal points in the outer wall of casing 41.

A third gear member 59 (FIG. 6) in meshing relation with the idler gear 54 is disposed beneath and in general alignment with said idler gear. This third gear is fixedly positioned adjacent the end of a cam shaft 60 within the confines of casing 41 and said cam shaft being rotatable is journaled in the inner side walls of casings 41 and 44 and that end of said cam shaft opposite said third gear member is journaled in the lower central portion of the outer wall of casing 44 (FIG. 2).

The first gear member 53 being a driven gear is caused to rotate in the direction of the indicating arrow shown in FIG. 6. This gear being in meshing relation with the idler gear 54 transmits its motion through said idler gear to the second and third gear members which are in mesh therewith causing them to rotate in the direction of the indicating arrows depicted in FIG. 6. Above and in general alignment with shafts 52 and 56 casing 41 is provided with a pair of drum shafts 61 and 62 which are supported in aligned apertures provided in the side walls of casing 41 and are fixedly positioned therein by means of set screws 63 provided in the inner wall of said casing (one only shown in FIG. 4). These drum shafts extend outwardly from casing 41 and on each side of casing 44 for a distance substantially that which the latter casing extends from casing 41.

The inner side wall of casing 41 is provided with a pair of generally circular milled pockets 64 and 65. The drum shaft 61 and 62 extend outwardly from the center of these pockets and support therein a pair of conventional Geneva wheels or rosettes 66 and 67, respectively.

A pair of cylindrical drum members 68 and 69 are rotatably received on the drum shafts 61 and 62 and are fixedly attached to the rosettes 66 and 67, respectively. The drum members are provided with sprocket teeth 70 and 71 at their ends (FIGS. 1, 3, and 4) which are adapted to enter the sprocket holes 72 and 73 adjacent the edges of the pattern cards for the purpose of advancing the same as said drum members are caused to rotate.

Those portions of shafts 52 and 56 which extend through and beyond the inner side wall of casing 41 are provided on each end thereof with conventional rosette drive cams 74 and 75, respectively. These drive cams are fixedly attached to their respective shafts and being in the form of discs, they are provided on the inner faces thereof with pin members 76 and 77 which extend in the direction of casing 41. Pockets 64 and 65 are provided with lower extended pockets 78' and 79', respectively, and provide clearance for the pin members 76 and 77 as they rotate with the rosette drive cams on shafts 52 and 56. With each revolution of these shafts, pins 76 and 77 are caused to engage a slot in the rosettes to advance the drum members 68 and 69 in increments equivalent to the parallel rows of pattern perforations on the pattern card material 29 in strip form containing the newly formed pattern perforations. The member 29 is caused to pass over drum 68 and the second master pattern card 78 is caused to pass over drum 69. Drum members 68 and 69 are provided on the outer periphery thereof with equally spaced longitudinal grooves 79 and 80 (FIGS. 3, 7, 8, and 9) which align with and underlie the pattern perforations in the cards as the latter are caused to pass thereover. The drum members are caused simultaneously to advance in increments in the direction of the indicating arrows depicted in FIG. 3 and the pattern perforations on the second master pattern card 78 are synchronized with those perforations on strip 29 so that the plurality of dual sensing members which will be fully described hereinafter will be comparing corresponding or like perforations during their vertical reciprocation.

The second master pattern card 78 utilizes a second weighted roll 81 to maintain said card in general vertical alignment with drum 69.

The pattern card strip 29 is caused to pass beneath an idler roller 82 (FIGS. 1 and 2) prior to passing over drum 68 and maintains said strip under a slight amount of tension while moving from the punching head to said drum. This roller spans the width of the pattern card strip 29 and is rotatably received onto an idler spindle 83. The spindle is attached to an arm 84 which extends in a generally rearward direction and at a right angle thereto. Arm 84 at its opposite end is fixedly attached to a cylindrical sleeve 85 which assembles on the drum shaft 61 within casing 41 and being oscillatable thereon, it provides a means for manually lifting the idler roller 82 out of contact with the pattern card strip 29.

That portion of cam shaft 60 within the confines of casing 44 is provided with a pair of cam members 86 and 87 (FIGS. 2 and 3) which are fixedly attached to said shaft and are caused to rotate therewith. A pair of collar members 88 and 89 are assembled on this shaft in abutting relation with the cams to prevent the possibility of said cams from moving inwardly away from their operating position.

The lower end of a pair of push rods 90 and 91 are in contact with cams 86 and 87, respectively. The push rods extend in a vertical direction through aligned apertures in a supporting cross member 92 which attaches to and extends between the side walls of casing 44. Push rod 90 extends through a guide member 93 and push rod 91 extends through a guide member 94 both of which are attached to the cross member 92 by means of cap screws 95 and 96, respectively (FIG. 2).

The upper portion of the push rods being threaded are adapted to assemble into the bottom of a lifting lever yoke 97.

Push rod 91 is provided at its upper extremity with an elongated threaded surface 98 and locking nut 99 which serves as a leveling adjustment for the lifting lever yoke 97.

Rotation of cams 86 and 87 causes the push rods to follow the contour of said cams to vertically reciprocate the lifting lever yoke 97. To maintain said push rods in contact with the cams, a coil spring 100 is provided intermediate said lever yoke and the cross member 92. This

coil spring is provided on each end thereof with threaded pin members 101 and 102, one of which assembles in the cross member 92 and the other in general alignment therewith in the bottom of the lifting lever yoke 97.

5 The lifting lever yoke 97 is provided with a pair of spaced parallel rod members 103 and 104 which extend the length of said lever yoke. These rod members are adapted to support a plurality of vertically disposed dual sensing levers generally indicated by numeral 105 and 10

equivalent in number to the maximum number of pattern perforations which can be made in a single row extending the width of a pattern card.

The sensing levers are shaped generally in the form of an inverted letter T and have upwardly directed spaced 15 slots 106 and 107 on the lower sides thereof which align with and are adapted to receive the rod members 103 and 104 therein (FIGS. 7, 8, and 9). The stem portions 108 of the sensing levers extend upwardly in a vertical direction with the terminal portions thereof being bifurcated 20 as at 109. Each sensing member is spring biased in a downwardly direction by a pair of coil springs 110 and 111. These springs are attached at one end to rearwardly and forwardly directed ears 112 and 113 which extend from and form an integral part of the stem portions 108 25 of the sensing levers. The opposite ends of these springs are attached to individual nibs provided on spring hook plates 114 and 115 which are assembled by means of cap screws 116 and 117 and clamping plates 118 and 119, respectively, to bar members 120 and 121 disposed below 30 ears 112 and 113 and which extend between the side walls of casing 44.

Due to the thickness of the sensing levers 105 and the plurality which are required for a pattern card, alternate sensing levers are provided with ears 122 and 123 (FIG. 3) which are like and serve the same purpose as ears 112 and 113 on the intermediate levers, but are positioned lower on the stem 108 to provide adequate side clearance for the plurality of coil springs 110 and 111 required. Like springs are attached to the ears of alternate sensing levers with the opposite ends of said springs being attached to the nibs of similar spring hook plates assembled in a like manner below and in vertical alignment with the lower anchoring means of the upper springs. The lower spring hook plates differ somewhat from the upper plates 118 and 119 and are depicted by numerals 45 124 and 125 in FIG. 3. These spring hook plates extend forwardly and rearwardly from their anchor points and, their outer surfaces being directed downwardly, are adapted to support lower sensing lever guides 126 and 127, respectively. These lever guides are provided with 50 a plurality of vertically disposed slots which are adapted to receive and guide the lower forwardly and rearwardly extending arms 128 and 129 which form the lower portion of each sensing lever 105 (FIGS. 7, 8, and 9).

An upper sensing lever comb or guide 130 having a 55 cross-sectional configuration that is generally L-shaped is attached to the forward upper portion of casing 44 by means of cap screws 131 and extends downwardly and thence inwardly to guide the upper bifurcated portion of the sensing levers in a plurality of horizontally extending 60 slots 130' provided for that purpose.

The outer and lower ends of the forwardly and rearwardly extending arms 128 and 129 which form an integral part of each sensing lever are provided with downwardly directed pattern sensing nibs 132 and 133 (FIGS. 65 7, 8 and 9).

The plurality of sensing levers 105 are raised and lowered in unison by the vertical reciprocation of push rods 90 and 91 acting on the lifting lever yoke 97 and the coil springs 110 and 111 maintain each lever in its 70 respective position on rod members 103 and 104 and within their guiding slots provided in each of the three guide members; however, said springs will permit a sensing lever to tilt slightly in a forwardly or rearwardly direction for 75 reasons to be more fully explained hereinafter.

The vertical reciprocation of the sensing levers is synchronized with the rotary movement of the drum members 68 and 69 and just prior to each downward movement of said levers the pattern card strip 29 and the second master card 78 are advanced by their respective drum members to place the next row of pattern perforations in alignment with the pattern sensing nibs 132 and 133. Where pattern perforations are present, the sensing nibs will pass therethrough and into the longitudinal grooves 79 and 80 which align with and underlie said pattern perforations (FIG. 8). Where no perforations are present, the sensing nibs will simply come into contact with the outer surface of the card members. Should a variation occur in the cards being compared, one sensing nib or the other of a lever would be caused to pass through an aligned perforation and the other would remain on the outer surface of its respective card (FIG. 9). A condition of this nature would tilt that particular sensing lever either forwardly or rearwardly depending, of course, on which card member was lacking a pattern perforation.

This tilting motion sets up a condition which initiates the stopping of the complete machine by means of an electrically controlled stop motion which will now be described in further detail.

FIGS. 10 and 11 are wiring diagrams of a conventional stop motion circuit showing by means of the heavier solid lines in FIG. 10 the flow of current during the actual running of the machine, and FIG. 11 shows the circuit change by similar lines which shuts the machine off should a variation in the cards being compared be detected.

During the actual running of the machine a source of 110 voltage is caused to flow through a transformer 134 which reduces it to approximately 12 volts. The start button 135 which may be of the conventional push or momentary contact type when closed causes the energizing of a relay 137. The energizing of this relay automatically moves the holding contacts 139 and 140 to the right-hand position as depicted in FIG. 10, and the holding contacts 139 being so actuated permit the so-called holding current to flow through the resistor 136 and thence to relay 137 while 140 controls the energizing of the solenoid 38 that is utilized in controlling the engaging and disengaging of the clutch 32 by means of lever member 33.

To stop the machine a horizontally disposed rod 141 extends through the bifurcated portion 109 of the sensing levers 105 and extending transversely of said levers the ends thereof are electrically insulated and supported in the side walls of casing 44.

Should a variation be detected in the cards being compared, a sensing lever will be caused to tilt as heretofore described and in so doing one side or the other of the bifurcated portion 109 of said lever will contact the rod 141 to complete another electrical circuit as depicted in FIG. 11.

Contact being made between a sensing lever and rod 141 draws the reduced voltage, leaving an insufficient amount to keep the relay 137 energized. The deenergizing of the relay causes the holding contacts 139 and 140 to move to the left-hand position as depicted in FIG. 11 thereby breaking the circuit to the relay, disengages the clutch 32 and permits the flow of current through these contacts of 139 and thence through the remainder of the stopping circuit as depicted by the heavier solid lines in said FIG. 2. This stopping circuit is provided with a telltale light 142 which goes on when this circuit is completed through to the ground G.

Additional elements within the electrical circuits of FIGS. 10 and 11 include a jog switch 135', a stop switch 135" and a resistor R which is in circuit with the telltale light 142. The start button 135 is a double contact type of switch and the contacts thereof are interconnected in a standard manner by means of a dotted line.

The plurality of sensing levers 105 supported by the lifting lever yoke 97 may, if desired to exchange pattern cards, be raised out of action by a mechanical means which comprises a hand lever 143 that protrudes outwardly through an L-shaped aperture 144 provided in the outer side wall of casing 44. Within this casing, hand lever 143 is pivoted attached adjacent its inner end as at 144 to a vertically disposed stud member 145 (FIG. 2). This stud is pivotally assembled in cross member 92 intermediate the push rod guide members 93 and 94. The hand lever is provided adjacent the innermost end thereof with a rearwardly directed pin 146 disposed at a right angle thereto and in general alignment with the lower end of a depending stud 147 assembled in the lifting lever yoke 97 intermediate the push rods 90 and 91. Hand lever 143 is normally in that position depicted by solid lines in FIG. 2 and is continually urged toward this position by a pair of coil spring members 148 (one only shown) which attach at one end to the upper portion of stud member 145 and the opposite end to said hand lever as at 149.

When this hand lever is manually moved to that position in FIG. 2 depicted by dot-and-dash lines, pin 146 is caused to push against the lower end of the depending stud 147 thus raising the lifting lever yoke 97 and the sensing levers supported thereby to an inactive position. This position is maintained by simply moving the hand lever slightly rearwardly which will place it beneath a notch 150 provided in said L-shaped aperture 144 (FIG. 3).

In operation, a strip of pattern card material is fed to the punching head of a conventional pattern card duplicating machine. The dictates of a first master pattern card are transmitted to the punching head by a plurality of indicating levers so that the same pattern perforations are formed in the pattern card strip as in said first master card.

This pattern card strip when leaving the punching head is directed to the verifying mechanism which comprises the invention and is caused to pass over a first drum member that is being advanced periodically and synchronously with a second drum member that is provided with a second master pattern card. A plurality of vertically reciprocating dual sensing levers are disposed above and in close proximity with the first and second drum members. On each downward stroke the dual sensing levers are adapted to detect the presence or absence of pattern perforations simultaneously in both the second master pattern card and the strip of pattern cards being compared. If no perforations are present, the sensing levers will simply come into contact with the outer surface of said cards and if perforations are present, the sensing nibs of the levers will pass through the cards and into the longitudinal extending grooves provided in the drum members which underlie and align with the parallel rows of pattern perforations. In the event of a variation in the pattern cards being compared, that sensing lever in alignment with said variation will on its downward movement be caused to tilt either forwardly or rearwardly depending on which card has the perforation.

The sensing levers, being bifurcated at their upper extremity and having an electrically controlled rod member passing transversely of and within the bifurcated portion, may tilt to contact said rod member. This contact completes an electrical circuit and initiates the stopping of the complete punching and verifying operation as heretofore described.

While the invention has been described as applied to a conventional pattern card punching or duplicating machine, it is to be understood that it is not to be so limited. The verifying mechanism may, for example, be used entirely alone to check a previously and independently formed pattern member against a master pattern. The drive for indexing the drums periodically may be derived from any suitable source in such a case. The stop motion

would be effective to stop the drive in any one of a number of possible ways.

While one embodiment of the invention has been disclosed, it is to be understood that the inventive concept may be carried out in a number of ways. This invention is, therefore, not to be limited to the precise details described, but is intended to embrace all variations and modifications thereof falling within the spirit of the invention and the scope of the claims.

I claim:

1. A means for verifying a perforated pattern card utilized in circular jacquard knitting machines comprising first and second drum members, said first drum member being adapted to support and guide a master pattern card and said second drum member being adapted to support and guide said first mentioned pattern card, a plurality of rockable dual sensing members disposed above said drum members, first means for vertically reciprocating said sensing members, a second means for advancing said drum members in timed relation synchronously with reciprocation of said sensing members for simultaneously comparing the perforations in said cards, an electrically controlled stop motion circuit for effecting the cessation of said verifying means should said sensing members detect a variation in said pattern cards, said electrically controlled stop motion circuit including an electrically energized rod member, whereby said sensing members are rocked so that they contact said rod member to complete the stop motion circuit in the event of a variation in said cards.

2. The mechanism according to claim 1 wherein said sensing members include a bifurcated upper end portion through which said electrically energized rod member is adapted to extend.

3. The mechanism according to claim 1 wherein said sensing members include first and second nib elements disposed in vertical and spaced relation, said first nib being adapted to enter a perforation in said first mentioned pattern card and said second nib being adapted to enter a perforation in said master pattern card.

4. In combination with a pattern card duplicating machine adapted to form parallel rows of punched pattern perforations on a pattern card according to the dictates of a first master pattern card functioning in conjunction with said machine, a pattern card verifier adapted to compare said pattern perforations with a second master pattern card comprising in combination first and second drum members, said first drum member being adapted to support and guide said second master pattern card and said second drum member being adapted to support and guide the newly formed perforated card, a plurality of dual sensing

members disposed above said cards and drum members, means for reciprocating said sensing members, said means comprising individual spring members for urging said sensing members toward said drum members and cam controlled rod members for raising said sensing members in unison, and a second means for periodically indexing said drum members in timed relation and synchronously with the reciprocation of said sensing members for detecting and comparing the perforations in said pattern card and second master card, said second means including a rosette wheel fixedly attached at one end of each said drums and gear driven cam members for rotating said rosettes in increments timed to the reciprocation of said sensing members and a further means for stopping said machine should said sensing members detect a variation in said card being compared, said further means including an electrically energized rod member extending transversely of and through said sensing members, said members being rockable in the event of a variation in said cards to touch said rod member and complete a stop motion circuit.

5. A means for verifying a perforated pattern card utilized in circular jacquard knitting machines comprising first and second drum members, said first drum member being adapted to support and guide a master pattern card and said second drum member being adapted to support and guide said first-mentioned pattern card, a plurality of dual sensing levers disposed above and spring biased toward said cards and drum members, cam controlled lifting rods for raising said levers in unison, cam controlled rosette members fixedly attached to one side of each said drum members for turning the latter synchronously and advancing said cards in increments timed to movement of said sensing levers, and an electrically controlled stop motion for effecting the cessation of said verifying should said sensing levers detect a variation in said cards, said electrically controlled stop motion including an electrically energized rod member extending transversely of and through the said sensing levers, said sensing levers being rockable in the event of a variation in said cards to touch said rod member to complete the stop motion circuit.
